WITNESS:

UNITED STATES PATENT OFFICE.

LEONARD DE LUCIA, OF WASHINGTON, DISTRICT OF COLUMBIA.

RUBBER HEEL.

Application filed January 20, 1923. Serial No. 614,005.

To all whom it may concern:

Be it known that I, LEONARD DE LUCIA, a subject of the King of Italy, residing at Washington, in the District of Columbia, have invented new and useful Improvements in Rubber Heels, of which the following is a specification.

My present invention has reference to an improved construction of rubber heels.

10 In carrying out my invention it is my purpose to produce a rubber heel having an outer rounded face provided, adjacent its perimeter with an enlargement and which has its inner face concaved and provided 15 with a plurality of projections which gradually decrease in size from the outer thickened face of the heel, said heel having embedded therein metallic plates arranged transversely of openings formed through the 20 heel and projections, said metallic plates adapted to reinforce the heel construction as well as to provide stops for the attaching 25 nails for the heel, while the projections prevent slipping by the wearer of the heel as well as longevity of life for the heel, it being necessary to wear the respective projections off before reaching the heel proper, therefore the slip preventing feature will remain with the heel for a considerable length of 30 time.

To the attainment of the foregoing, and other objects which will present themselves as the nature of the invention is better understood, reference is to be had to the 35 drawings, which accompanies and which forms part of this application:—

In the drawings:—

Figure 1 is an outer face view of a rubber heel in accordance with this invention.

40 Figure 2 is an inner face view thereof.

Figure 3 is a sectional view on the line 3—3 of Figure 1.

In the drawings, I have illustrated one form of my improvement, it being molded 45 in the usual manner.

In the construction disclosed the heel is indicated by the numeral 1, the same having its outer ends slightly rounded both longitudinally and transversely, while its inner face is concaved. The outer face is indicated by the numeral 2 and is formed, at a suitable distance inward of its edges with a thickened tread portion 3. The tread surface 3, at preferably equi-distant points, is provided, with outwardly projecting lugs 8 and reduced bosses 9 arranged centrally on the outer face of each lug. The lugs and bosses provide calks to prevent slipping of the wearer of the heel. In aline centrally with each boss and lug the heel has an opening 10 thereto, and this opening is bridged by a disc 11 arranged in the heel adjacent the inner surface thereof when the same is molded. Each metal disc 11 has a central opening therethrough for the reception of 50 the securing nails.

It is thought that the foregoing description when taken in connection with the drawings will amply set forth my heel construction and the advantages thereof.

Having thus described my invention what I desire to claim as new is:—

A rubber heel of the character described comprising a body having its outer face slightly rounded both longitudinally and transversely while the inner face thereof is concaved, a thickened tread portion formed on the outer face of the body, a plurality of equi-distantly spaced outwardly projecting lugs arranged adjacent the perimeter of the 75 thickened tread, reduced bosses rising centrally from the outer face of each lug and together with the projections provide a non-slipping surface, said lugs and bosses being provided with a centrally disposed opening 80 which extends through the tread and body, and means for reinforcing the openings as and for the purpose specified.

In testimony whereof I affix my signature.

LEONARD DE LUCIA.
